CLAIM

The ornamental design for a visual indicator for an above-ground storage tank, as shown and described.

DESCRIPTION

FIG. 1 is a perspective view of a visual indicator for above-ground storage tanks;

FIG. 2 is an exploded view thereof;

FIG. 3 is a front view thereof;

FIG. 4 is a rear view thereof;

FIG. 5 is a side view thereof; and,

FIG. 6 is a front view thereof installed on an above-ground storage tank.

The broken lines used for the above-ground storage tank in FIG. 6 is included for the purpose of illustrating environmental structure while all other broken lines illustrate portions of the visual indicator for above-ground storage tank; the broken lines form no part of the claimed design.
